STORAGE BIN FOR BATHROOM IMPLEMENTS

Georg Weihrauch, Burgermeister, Arnold-Strasse,
6949 Aschbach, Odenwald, Germany

Filed July 19, 1971, Ser. No. 164,212

Term of patent 7 years

Int. Cl. D6—04

U.S. Cl. D6—86

FIG.1

FIG.5

FIG. 1 is a perspective view of a storage bin for bathroom implements showing the front side of my new design, the other side being identical;

FIG. 2 is a rear elevational view thereof;

FIG. 3 is a side perspective view thereof, with the front cover tilted open to show the interior;

FIG. 4 is an elevational view of the inside of the tilting door thereof; and

FIG. 5 is a front elevational view thereof, with the tilting door removed for convenience of illustration.

I claim:

The ornamental design for a storage bin for bathroom implements, as shown and described.
